UNITED STATES PATENT OFFICE.

ELMER E. ALLEN, OF FLUSHING, NEW YORK.

ROTARY ENGINE.

1,234,599.

Specification of Letters Patent. Patented July 24, 1917.

Application filed November 18, 1916. Serial No. 132,112.

To all whom it may concern:

Be it known that I, ELMER E. ALLEN, a citizen of the United States, and a resident of Flushing, in the county of Queens and 5 State of New York, have invented certain new and useful Improvements in Rotary Engines, of which the following is a specification.

My improvements relate to rotary engines 10 of the segmental piston and revoluble casing type, and are designed to simplify their construction and render them effective and economical in operation. The invention consists in the specific construction and arrangement of parts hereinafter described and claimed, distinctive features being the means by which a duplex impetus is imparted to the rotor during each rotation, and by which the motive power is supplied and 20 the exhaust effected, all as hereinafter fully set forth.

In the accompanying drawings, Fig. 1, is a plan of the engine; Fig. 2, is a plan of the rotor partly broken 25 away and shown in section on plane of line 2—2, Fig. 10; Fig. 3, is a section taken upon plane of line 3—3, Fig. 4;

Fig. 4, is an elevation of the annular cap 30 plate for the feed channel;

Fig. 5, is a half section and half elevation of the duplex abutment member;

Fig. 6, is a sectional elevation taken upon 35 plane of line 6—6, Fig. 5;

Fig. 7, is a detail showing the interlocking of the abutment packing at the peripheral edge of said abutment;

Fig. 8, is a sectional elevation taken upon 40 plane of line 8—8, Fig. 10;

Fig. 9, is a sectional elevation taken upon plane of line 9—9, Fig. 10;

Fig. 10, is a sectional elevation taken upon 45 plane of line 10—10, Fig. 11;

Fig. 11, is a front view of the motor;

Fig. 12, is a section taken upon plane of 50 line 12—12, Fig. 10;

Fig. 13, is a rear elevation of the motor;

Figs. 14, to 17, inclusive are diagrammatic 55 views illustrating successive periods during one cycle of operation.

The bed plate B, supports two standards B', B'', upon and between which the operative parts of the motor are mounted. Rigidly attached to what may be designated 60 for convenience of description as the front standard B', is a fixed journal a, formed in-

tegral with the stationary gear a', at its inner extremity. On this rigid journal a, between the said stationary gear a', and the head b', of the standard B', is positioned the hub c, of the crank and gear chamber casing C. The other or rear standard B'', is formed with a bearing b'', in which is journaled the power shaft P, the inner end of which is secured rigidly to the port head or rear cap 65 plate D. Between the edges of this rear cap plate D, and the opposed edges of the crank and gear chamber casing C, is rigidly secured the piston cylinder or drum E, so that said gear casing C, piston cylinder E, 70 rear cap or port plate D, and power shaft P, are all rigidly connected together and free to rotate in unison upon and between the stationary journal a, on the front standard B', and the bearing b'', on the rear standard 75 B''.

In the piston cylinder or drum E, and between the crank and gear chamber casing C, and the port plate D, and rigidly secured to all three of them, is the piston and valve 80 section G, which is formed with the piston sections g¹, g², between the outer opposed surfaces of which are the expansion chambers g³, g⁴.

The segmental abutments L', L'', are 85 rigidly attached to a common hub l, which is keyed to the main crank shaft h, journaled in the port plate D, the piston section G, and the center of the stationary gear a', and in axial alinement with the power shaft 90 P, as will be seen by reference particularly to Fig. 10. The wrist pin of the crank h', of said main crank shaft h, is connected by rod j, with the wrist pin of an auxiliary crank k, the journals k', k'', of which are 95 mounted in bearings (see Fig. 10) in the abutment section G, and in the crank and gear chamber casing C. This auxiliary crank k, carries rigidly attached to one of its journals k', a planetary pinion k³, which 100 meshes with the stationary gear a', and is of one half the diameter of the latter. The other journal k'', of the auxiliary crank k, has rigidly attached to it a driving pinion 105 h⁴, which meshes with a gear wheel m', on the valve-cam shaft m, said gear wheel m', being twice the diameter of said driving pulley k⁴. There is no auxiliary crank on the opposite side of the main crank shaft h, but a planetary gear k²², like unto the first 110 named, k'', meshes with the stationary gear a', being mounted on a countershaft k'',

journaled in and between the piston section G, and the gear chamber casing C, said countershaft k'' , having rigidly mounted thereon the driving pinion k^{44} , (which is a 5 duplicate of the first named drive pinion k^4 , on the journal k^2 , of the auxiliary crank k ,) said driving pinion k^{44} , meshing with a gear m^2 , of twice its diameter, mounted on the valve cam shaft m^3 .

10 The transverse radial walls g , g' , on one side and the corresponding wall g , g' , on the other side of the section E, are all convergent toward the axis of the main crank shaft h , forming diametrically opposed segmental piston sections g^4 , g^5 , in which are situated in each case an inlet valve i , and port i' , and an exhaust valve e , and port e' , both of said valves in each case opening into a common valve chamber v , formed with a 15 port v' , opening in one case into the abutment chamber g^2 , and in the other into the other abutment chamber g^3 . The valves are of the spring puppet type, and are actuated by suitably timed cams on the shafts m , and 20 m^3 , respectively, in a manner well known in the art. The discharge ports e' , open into the atmosphere; the inlet ports i , i' , are supplied with gas through conduits d , d' , communicating with an annular groove d' , 25 formed in the head D, which groove is closed by an annular cap plate d^2 , provided with a coupling pipe d^3 , which connects the gas chamber or groove d' , with a source of supply, indicated by the port d^4 , in Figs. 3, 30 and 10, and by the pipe d^5 , in Fig. 13. The annular closure plate d^2 , is held against the edges of the annular groove or feed chamber d' , by elastic resilient pressure, as by the 35 springs d^6 , d^7 , interposed between said annular plate d^2 , and stationary parts of the apparatus, such as bracket heads d^8 , d^9 , indicated in Figs. 1, 3, 4, and 13, of the drawings.

The segmental abutments L' , L^2 , and hub 45 l , may be made solid, as shown in Fig. 8, mainly therein for simplicity and clearness of illustration, or the segments may be hollow as is the duplex abutment section as shown in Fig. 5. In either case the ends of 50 the hub l , and of the abutment sections L' , L^2 , as well as their peripheral edges are grooved to contain suitable packing q , to insure a gas tight fit between them and the inner face of the head D, on one side, the 55 inner face of the abutment member E, on the other side, and the inner side of the piston cylinder E.

The auxiliary or planetary gears k^3 , and k^{22} , being only of one half the diameter of 60 the fixed gear a' , with which they mesh, will obviously each rotate twice while making a single revolution around said stationary gear a' , while the gears m' , and m^2 , on the valve cam shafts m , and m^3 , being twice the 65 diameter of their driving pinions k^4 , k^{44} , it

is likewise obvious that said valve cam shafts will be rotated only once during each revolution of the planetary gears k^3 , k^{22} around said stationary gear a' ; and the timing is such that a charge of gas will be admitted to 70 each expansion chamber g^2 , g^3 , exploded, and ejected therefrom during each rotation of the rotor D, E, C, considered as a whole. A spark plug s , is provided for each of the valve chambers v , properly timed with relation 75 to the operation of the valve cams, etc.

The diagrams Figs. 14, to 17, inclusive illustrate collectively four successive periods in a single rotation of the rotor shell, the arrow heads s' , s^2 , in each case indicating the 80 points of firing of the compressed charges of gas. Thus the period from Fig. 14, to Fig. 15, represents that of expansion; the period between Figs. 15, and 16, that of the ejection of the products of combustion; the 85 period between Figs. 16, and 17, that of the induction of fresh fuel; and that between Figs. 17, and 14, the period of compression.

The function of the planetary gear k^3 , auxiliary crank k , pitman j , and main crank 90 h' , is to effect and control the intermittent action of the abutments L' , L^2 , which they do by alternately holding them as related to the continuously rotating motor-shell D, 95 E, C, and the piston section G, (which are united as hereinafter stated, and hence rotate together around the axis of the motor) and then advancing them twice during each rotation of the shell.

For instance, starting with the relative 100 position of parts shown in Fig. 14, in which the charges of gas have already been received and compressed between the abutments L' , L^2 , and within the valve chambers v , and passages v' , of the piston sections g^4 , 105 g^5 , the ignition and expansion of the charges forces the piston sections g^4 , g^5 , over into the position shown in Fig. 15, the planetary gear k^3 , and connections holding the abutments L' , L^2 , as related to the casing, as 110 will be understood by reference to the dotted lines in Figs. 14, and 15, by which it will be seen that this partial revolution of the planetary gear k^3 , has not altered the position of the main crank h' , which it will be remembered is connected rigidly with hub l , of said abutments L' , L^2 , thus enabling the abutments to resist the expansive force so that the latter is exerted to effect the advance of the piston sections g^4 , and g^5 , and 115 hence of the shell. During the quarter rotation from the positions shown in Fig. 15, to those shown in Fig. 16, the continued rotation of the planetary gear k^3 , causes its connections to pull the abutments L' , L^2 , over for half a rotation, causing the latter to expel the products of combustion from the piston chambers g^2 , g^3 . During the next quarter rotation of the shell and piston sections 120 g^4 , g^5 , the continued revolution of the plan- 125 130

etary gear k^3 , around the stationary gear a' , again holds the abutments as shown in Figs. 16, and 17, and as illustrated again by the dotted positions of the cranks and connection rod. As the piston sections g^4 , g^5 , recede from the abutments and from their positions shown in Fig. 16, to those shown in Fig. 17, they suck in the fresh charges of gas, which charges are compressed when the 10 abutments are again advanced by the continued revolution of the planetary gear k^3 , from the positions shown in Fig. 17, to the original positions shown in Fig. 14, from which the tracing of the cycle of rotation 15 was begun, it being understood that the rotor acts as its own fly wheel, and that the impetus imparted thereto is evenly balanced on diametrically opposite sides thereof.

By this means I obviate dead centers and 20 attain a smooth running rotor in which full efficiency is attained—it being of course understood that the operations of the inlet and discharge valves are properly timed to effect these results. Furthermore the initial force 25 of the explosions being exerted peripherally is applied to the best advantage, and angular frictional resistance is obviated.

I have herein described my motor as 30 driven by means of explosive gas as a source of power, although it is obvious that by modifying the valve service other gas under pressure, as steam, may be substituted as a source of power.

What I claim as my invention and desire 35 to secure by Letters Patent is,

1. In a rotary engine of the character designated, in combination, a casing comprising a crank and gear compartment, a piston cyl-

inder and a port cap plate all rigidly connected to form a rotative unit, a stationary 40 gear, a planetary gear engaging therewith, an auxiliary crank carried by said planetary gear, a rod connecting said auxiliary crank with a main crank, said main crank rigidly connected with diametrically opposed seg- 45 mental abutments, diametrically opposed piston sections integral with the casing, a power shaft attached to said casing, and cam means actuated from said planetary gears for effecting the inlet, expansion and 50 discharge of a gaseous source of power.

2. In a rotary engine of the character designated, in combination, a casing comprising a crank and gear compartment, a piston cylinder and a port cap plate all rigidly 55 connected to form a rotative unit, a stationary gear, planetary gears engaging therewith, an auxiliary crank carried by one of said planetary gears, a rod connecting said auxiliary crank with a main crank, said 60 main crank rigidly connected with diametrically opposed abutments, said abutments, diametrically opposed piston sections integral with the casing, inlet and discharge valves positioned in each of said piston sections, valve cam shafts mounted in the latter and actuated by gearing deriving motion 65 from said planetary gears, and a power shaft attached to said casing in axial alignment with the abutment shaft and said stationary gear.
